(57) **CLAIM**

The ornamental design for a display panel with icon, as shown and described.

DESCRIPTION

FIG. 1 is a front view of a display panel with icon, showing my new design; and,

FIG. 2 is an enlarged front view thereof, the icon is shown separately for clarity of illustration.

The broken lines in FIG. 1 showing the display panel form no part of the claimed design. The remaining broken lines showing portions of the icon form part of the claimed design.
